UNITED STATES PATENT OFFICE.

WILLIAM J. BALDWIN, OF BROOKLYN, AND JAMES M. TAGGART, OF EAST WILLISTON,
NEW YORK.

GREASE-SEPARATOR.

1,119,565.

Specification of Letters Patent.

Patented Dec. 1, 1914.

Application filed April 8, 1913. Serial No. 758,574.

To all whom it may concern:

Be it known that we, WILLIAM J. BALDWIN and JAMES M. TAGGART, both being citizens of the United States, and residents, respectively, of the borough of Brooklyn, city and State of New York, and of East Williston, county of Nassau, State of New York, have invented certain new and useful Improvements in Grease-Separators, of which 10 the following is a specification.

This invention relates to improvements in grease separators.

It is the purpose of the invention to provide apparatus for the removal of oil and 15 greasy matters, which for brevity we herein-after designate by the term "oil", from exhaust steam, so that the steam, after the removal of said oil, may be the more suitable for various commercial purposes, as for 20 making artificial ice, for drying and heating purposes, for supplying steam boilers, and for other purposes for which the use of greasy, oily water is unsuitable.

It is the further purpose of the invention 25 to provide for collecting and preserving the oil, so that it may be again utilized, and also so that it shall not clog drains or cause other injurious results.

We accomplish the several purposes by 30 causing the exhaust steam containing the oil to be projected upon the surface of clean water, to which the oil adheres by reason of its affinity for the water; the steam being thereby freed from the oil and then going 35 by its proper outlet to condensers or other apparatus. In order that the operation of the grease separator may be continuous, it is necessary that a clean water surface, free from oil, be continuously presented to the 40 incoming steam; and in order to effect this result it is necessary that the oil which has been previously brought into the separator shall be continuously carried away from contact with the successively entering ex- 45 haust steam, and that the said oil shall be prevented from forming a film over the surface of the clean water. We effect the removal of the oil from the path of the incoming steam, and prevent the forming of such 50 film of oil on the surface of the clean water, by the use of pans, preferably a plurality, located within the closed shell of the separator and directly in the path of the incoming exhaust steam, and substantially concentric 55 to said inlet of the exhaust steam, so that

the steam projects at considerable velocity directly on the surface of the water in the pans; the impact of steam on the surface of the water producing a surge or wave and flow radially and outwardly from the center 60 over all parts of the edges of the pans, whereby the oil, which was in the exhaust steam, is caught upon the surface of the water in the pans and carried outwardly over the edges of the pans, being finally collected on 65 the surface of the water in the body of the separator outside of the pans and carried away by its proper oil outlet. Thus, also, the said radial wave or surge continually presents clean water to the incoming steam, 70 and there results a continuous separation of oil from the steam; whereas, if there were not the aforesaid radial wave or surge and flow of the water over the edges of the pans, the water in the path of the incoming steam 75 would soon be coated with such a film of oil that it would not properly take up more oil from the incoming steam, and the separation of the oil from the steam would be impaired. Therefore the continuous radial 80 outward flow of the greasy water is a valuable aid in the continuous and effective separation of the oil from the exhaust steam, and the means to effect it is an important 85 feature of our invention.

To collect and preserve the oil provision is made for draining it off separately from the water which condenses in the separator, as will be hereinafter explained. Other features and details of the invention are also 90 illustrated in the accompanying drawings and will be hereinafter described.

Referring to said drawings, to aid the description, Figure 1 is an elevation of a grease separator having a plurality of pans; Fig. 2 is a horizontal section and plan of the same on the plane of the line 2-2 of Fig. 1; Fig. 3 is a horizontal section and plan of the same on the plane of the line 3-3 of Fig. 1.

A is a closed vessel constituting the body of the grease separator, made of material of sufficient strength to sustain any desired pressure. Said vessel A is preferably, but not necessarily, of cylindrical horizontal cross section, and is provided with an inlet nozzle or pipe a, which may be connected with a pipe supplying exhaust steam to the vessel A. A conoidal deflector B may be secured at the inner end of said inlet a, to 110

prevent the short circuiting of the exhaust steam from the said inlet *a* to the outlet *b*, and to insure the spreading of the exhaust steam radially in all directions. One or 5 more pans is or are located in said vessel A, below said inlet *a*, and in the path of the entering exhaust steam. In small grease separators a single pan may be employed, but in larger grease separators it is preferable 10 to use a plurality of pans; and three such pans, respectively indicated by C, D and E are illustrated in Fig. 1 of the said drawings. Said pans C, D and E are supported in any suitable manner, as by legs as 15 illustrated, and are preferably, but not necessarily, arranged concentrically to the axis of said exhaust steam inlet *a*, and the upper edges of said pans are progressively lower from the innermost to the outermost 20 pan, as indicated in Fig. 1. The upper edge of each pan is also preferably, but not necessarily, level, so that there shall be an overflow of oil and water evenly over all parts of the edge of each pan, and also a radial motion of the water and oil outwardly toward all parts of said edge. In Fig. 1 said 25 pans, C, D and E, are shown as each having its own closed bottom, but the pans might be made, if desired, with one common bottom; it only being necessary that the top edges of the pans be progressively lower from the innermost to the outermost 30 pans; and the pans might also be of any other suitable shape without departing from 35 our invention.

It is frequently desirable to supply fresh water to the pans, in addition to the water which is precipitated in them from the incoming exhaust steam; and this may be effected by connecting a supply pipe I with the innermost pan C, as indicated in Fig. 1, *i* being a valve on said pipe I, to control the supply of fresh water, and said pipe I being connected with any suitable water supply. Said pipe I can also be arranged by use of proper valves as *I'* and branches, if desired, to serve both as a drain and as a water supply pipe, to facilitate cleaning the pans.

To produce the most efficient and regular 50 operation of the apparatus the level of the water *W* *L* in said vessel A should be uniform, and this is effected by the overflow F, which is preferably constructed with the downward branch *e*, which descends into the 55 water below the level at which the oil will collect, and with the upward branch *f*, to prevent siphoning. The said overflow F may be connected with a suitable pipe leading to any desired place. To draw off the 60 collected oil a suitable oil draw-off cock G is provided, located at the water level as determined by said overflow F. The oil collects on the surface of the water in vessel A, and is drawn off by said cock G.

65 H is a drain and washout pipe provided

with a suitable valve, and by means of which the contents of the vessel A may be drained off and said vessel A be cleaned.

The apparatus operates as follows: The exhaust steam entering by inlet *a* projects directly upon the water in said pans C, D and E, and the oil separates from the steam and collects on the surface of the water in the pans. The impact of the incoming exhaust steam, with its contained condensed water and oil, upon the surface of the water in the pans causes the accumulating oily water to surge and flow continuously radially outwardly and over the edge of each pan, thereby continually carrying the oil away from the path of the incoming steam, and continually presenting clean water to the incoming steam, so that the separation of the oil from the steam is continuous. The steam from which the oil has separated goes by the outlet *b* to the desired place of use. The oil collects on the top of the water in the main body of the vessel A, outside of the pans and out of contact with the incoming steam, and is drawn off from time to time by the draw off cock G.

Whenever it is desired to supply fresh water to the pans, to increase the rapidity of flow over the edges of the pans, and insure the rapid removal of the oil from the pans, fresh water can be supplied by the pipe I. By means of the overflow F the water in said vessel A is maintained at a uniform level, so that the oil can always be drawn off by said cock G, and that the water will never rise in said vessel A so high as to cover said pans C, D or E.

Now having described our improvements, we claim as our invention.

1. The combination in a grease separator 105 of a closed vessel provided with an inlet for exhaust steam, and with an outlet for steam from which the oil has been separated, a pan substantially concentric to said inlet and in the direct path of the exhaust steam, 110 and adapted to contain water to catch the oil from said steam; and an oil outlet from said vessel at a lower level than the surface of said pan, substantially as described.

2. The combination in a grease separator 115 of a closed vessel provided with an inlet for exhaust steam, and with an outlet for steam from which the oil has been separated, a pan substantially concentric to said inlet and in the direct path of the exhaust steam 120 and adapted to contain water to catch the oil from said steam, an oil outlet from said vessel at a lower level than the surface of said pan, and a non-siphoning overflow from said vessel at the same level as said oil outlet, substantially as described.

3. The combination in a grease separator 130 of a closed vessel provided with an inlet for exhaust steam, and with an outlet for steam from which the oil has been separated, a

pan substantially concentric to said inlet and in the direct path of the exhaust steam and adapted to contain water to catch the oil from said steam, an oil outlet from said vessel at a lower level than the surface of said pan, and a non-siphoning overflow from said vessel at the same level as said oil outlet, and a conoidal deflector on said inlet for exhaust steam substantially concentric to said inlet and located between said pan and said outlet for steam from which the oil has been separated, substantially as described.

4. The combination in a grease separator, of a closed vessel provided with an inlet for exhaust steam and with an outlet for steam from which oil has been separated, a plurality of pans in the direct path of the incoming steam substantially concentric to said exhaust steam inlet and the upper edges of said pans being successively lower from the inner to the outer pan, and an oil outlet from said vessel at a lower level than the water surface of the lowest pan, substantially as described.

5. The combination in a grease separator, of a closed vessel provided with an inlet for exhaust steam and with an outlet for steam from which oil has been separated, a plurality of pans in the direct path of the incoming steam substantially concentric to said exhaust steam inlet and the upper edges of said pans being successively lower from the inner to the outer pan, and a non-siphoning overflow from said vessel at the same level as said oil outlet, and a conoidal deflector on said inlet for exhaust steam substantially concentric thereto and located between said pans and said outlet for steam from which the oil has been separated, substantially as described.

5. The combination in a grease separator, of a closed vessel provided with an inlet for exhaust steam and with an outlet for steam from which oil has been separated, a plurality of pans in the direct path of the incoming steam substantially concentric to said exhaust steam inlet and the upper edges of said pans being successively lower from

the inner to the outer pan, an oil outlet from said vessel at a lower level than the water surface of the lowest pan, and a non-siphoning overflow from said vessel at the same level as said oil outlet, substantially as described.

6. The combination in a grease separator, of a closed vessel provided with an inlet for exhaust steam and with an outlet for steam from which oil has been separated, a plurality of pans in the direct path of the incoming steam substantially concentric to said exhaust steam inlet and the upper edges of said pans being successively lower from the inner to the outer pan, an oil outlet from said vessel at a lower level than the water surface of the lowest pan, a non-siphoning overflow from said vessel at the same level as said oil outlet, and a conoidal deflector on said inlet for exhaust steam substantially concentric thereto and located between said pans and said outlet for steam from which the oil has been separated, substantially as described.

Signed at New York city, in the county of New York and State of New York this 25th day of March, A. D. 1913.
